UNITED STATES PATENT OFFICE.

WILLIAM T. VAN DORN, OF CHICAGO, ILLINOIS, ASSIGNOR TO VAN DORN GIRDER PLATE COMPANY, A CORPORATION OF ILLINOIS.

AUXILIARY FLOOR FOR RAILWAY-CARS.

1,259,935.

Specification of Letters Patent. Patented Mar. 19, 1918.

Application filed December 29, 1917. Serial No. 209,417.

To all whom it may concern:

Be it known that I, WILLIAM T. VAN DORN, a citizen of the United States, residing at Chicago, county of Cook, State of Illinois, have invented a certain new and useful Improvement in Auxiliary Floors for Railway-Cars, and declare the following to be a full, clear, and exact description of the same, such as will enable others skilled in the art to which it pertains to make and use the same, reference being had to the accompanying drawings, which form a part of this specification.

My invention has for its object to produce a simple, novel and inexpensive construction and arrangement by means of which an auxiliary ventilated flooring becomes a permanent part of the car but, when not required, may quickly and easily be stored in the upper regions of the car and be securely held there; whereby the auxiliary floor will always be at hand when needed and, when it is not needed, it will be held out of the way so as to permit the car to be loaded to its maximum capacity and at the same time avoid the possibility of damaging the auxiliary flooring through contact with the contents of the car.

In carrying out my invention I make use 30 of an auxiliary flooring which is divided along the longitudinal center of the car in the same manner as the type of flooring now in use in which the sections are hinged at opposite sides of the car and are adapted to be 35 swung up against the sides of the car, just above the main floor, when not in use. Therefore, viewed in one of its aspects, my invention may be said to have for its object to produce a simple, novel and inexpensive 40 expedient for mounting auxiliary floors of this old type, either originally or after they have gone into use, in such a manner that when not in use they may quickly and conveniently be stored in an out of the way place instead of taking up some of the most valuable space in the car, as heretofore.

The general objects of my invention are the same as those set forth in my previous application Serial No. 206,130, filed December 8, 1917, the same or similar ends being 50 accomplished in a somewhat different and perhaps simpler way. Therefore, viewed in one of its aspects, my invention may be said to have for its object to simplify and improve on the means shown in my aforesaid

application for mounting sectional auxiliary flooring so as to make it a permanent part of the car and permit it to be stored in the upper regions of the car when not in use.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a view of a refrigerator car, partly in longitudinal section and partly in side elevation, containing my improved auxiliary flooring, one-half of the flooring being shown in position on the main floor of the car and the other half being shown stored out of the way;

Fig. 2 is a top plan view of the auxiliary flooring when it is resting on the main floor of the car;

Fig. 3 is a section taken approximately on line 3—3 of Fig. 1;

Fig. 4 is a section on an enlarged scale 80 taken approximately on line 4—4 of Fig. 1;

Fig. 5 is a section taken approximately on line 5—5 of Fig. 4;

Fig. 6 is a section on an enlarged scale 85 taken approximately on line 6—6 of Fig. 1, showing only the lower end of the auxiliary flooring and the locking support;

Fig. 7 is a section, on an enlarged scale, taken approximately on line 7—7 of Fig. 1, showing one of the sliding hinges;

Fig. 8 is a section, on an enlarged scale, taken approximately on line 8—8 of Fig. 1, showing one of the sliding hinges between the side of the car and one of the central auxiliary floor sections;

Fig. 9 is a view similar to Fig. 1, showing a modified arrangement; and

Fig. 10 is a transverse section through the car shown in Fig. 9, a portion of the auxiliary floor being shown down and another 100 portion being shown in its raised position.

Referring first to the construction shown in Figs. 1 to 7, 1 represents a railway car having a floor, 2, side walls, 3, and end walls, 4. An auxiliary flooring adapted to cover the entire floor of the car is made up of two end sections, 5, 5, each of which lies adjacent to one of the end walls of the car, has a length equal to the width of the car, and a width at least as great and preferably greater than 110

one-half the width of the usual side door of the car, together with four additional sections, 6, filling the space between the two end sections and divided along the longitudinal and transverse axes of the car.

All of the auxiliary floor sections are attached to the corresponding walls of the car in such a way as to be connected permanently thereto while having capacity for swinging movements up against the walls of the car and subsequent vertical sliding movements to bring them into the upper regions of the car. This is conveniently accomplished by placing in each end and side wall vertical guides, 7, there being at least one guide and preferably more, for each auxiliary floor section. These guides extend upwardly from points near the main floor of the car to any desired height. Interlocked with the guides, as best shown in Figs. 7 and 8, are shoes or heads, 8, which can slide up and down but are held against displacement laterally of the guides. The end sections, 5, of the auxiliary flooring are connected to the corresponding guiding heads by suitable hinge joints, 9. The auxiliary floor sections, 6, are connected to the corresponding guide heads by hinge joints which, as best shown in Fig. 8, permit relative sliding movements between the sections and the guide heads longitudinally of the car. In the arrangement shown, each of the guide heads or shoes has a hinge knuckle, 10, through which passes an elongated pintle, 11, secured at its ends to the corresponding auxiliary floor section. The length of these pintles is equal to and preferably somewhat greater than one-half the width of the ordinary side door of a railway car.

It will be seen that the connections between the auxiliary floor sections and the car are such as to permit the auxiliary floor to rest upon the car floor in the usual way. When the car is to be loaded with other goods than those requiring the auxiliary floor, so that it is desirable to have the auxiliary floor removed from the main floor of the car, the end sections are swung upwardly on their hinges so as to lie against the end walls of the car and are then slid upwardly along these end walls until their upper edges lie close to the car ceiling as shown at the right hand end of Fig. 1 and in Fig. 3. Suitable means are provided for holding the end sections in these raised positions. After the end sections have been stored out of the way, the four remaining sections are moved longitudinally so as to carry them out of the space lying between the opposed doorways, such movement being permitted by the elongated hinges, and each of these four sections is then swung up against the side of the car and slid upwardly in the same manner as the end sections. In Fig. 1, one of the sections, 6, in the right hand half of

the car, is shown in its raised position while the corresponding section in the other end of the car still projects to the transverse center of the car, that is, halfway across the space between the doorways. After the left hand end section, 5, in Fig. 1, has been stored in the same manner as the right hand end section, then the two left hand sections, 6, may be slid toward the left until the doorways are cleared, the raising of these sections being then effected in the same manner as in the case of the other sections.

The various auxiliary floor sections may be held in their raised positions in any suitable way. I prefer to provide suitable stationary guides or ways which are grooved or otherwise constructed so as to receive the vertical edges of each section as it is slid upwardly along the corresponding wall of the car; thus holding the raised auxiliary flooring against the walls of the car and preventing them from tilting outwardly. This not only relieves the holding and supporting devices that may be supplied, but it protects the workman in that it insures that the only movement that an auxiliary section can make after it has been started upwardly along the wall of the car, is an upward movement or a downward movement. In the arrangement shown, the guides or ways for the four sections that fold up against the sides of the car are indicated at 13. They may conveniently consist of Z-bars as shown in Fig. 5, or take any other suitable form. The guides or ways for the two end sections may be simple bars or cleats, 14, secured to the side walls of the car at a distance from the end walls equal to the depth or thickness of the auxiliary floor.

Any suitable means may be provided for preventing the auxiliary floor sections from dropping down from their raised positions. In the arrangement shown, there are automatic locks, 15, distributed at intervals around the walls of the car in the plane of the lower edges of the auxiliary floor when the latter is in its stored position. One of these locks is shown in Fig. 6, comprising a spring-held dog, 16, pivotally mounted in a recessed casting, 17, set into the wall of the car and tending normally to project outwardly and engage with the under edge of the floor section when the latter is raised. The dogs yield when the floor sections are moved upwardly, so as to permit the latter to pass, but afford rigid supports for the lower edges of the floor sections after they have passed into the position shown in Fig. 6. The locking dogs may be swung into inoperative positions by means of combined unlocking and trip arms, 18, each pivotally connected to one end of a corresponding locking dog so that when swung in the positions shown in dotted lines in Fig. 6 it causes the locking dog to be swung back into the

recess in the casting 17 and holds it there until the descending floor section trips it and throws it back into the position shown in full lines in Fig. 6; the locking dog 5 springing outwardly from the dotted line position to the full line position as soon as the upper end of the floor section has passed.

In the arrangement illustrated in my aforesaid application, the exposed face of 10 the auxiliary sections, when the latter are in their stored positions, is that which forms the top surface of the auxiliary floor when the auxiliary floor is resting on the main floor. This is because each floor section is 15 folded or rolled through three-quarters of a complete turn. In the present arrangement the rolling or folding is through only a quarter of a turn and therefore the exposed face, when a section is in its stored 20 position, is the bottom side of the section instead of the top side. Consequently, in the present arrangement, the stringers or beams on which the floor slats are secured are exposed when the auxiliary floor is in its stored 25 position. For the purpose of bracing the floor stringers or beams and providing a comparatively smooth exposed surface or face when the auxiliary floor is stored in the top of the car, I secure cross pieces or slats, 30 20, on the under side of the floor stringers or sills, 21, these slats being preferably countersunk as best shown in Fig. 5, so as to lie flush with the bottom edges of the beams or sills.

35 In Figs. 9 and 10 I have illustrated an arrangement which avoids the use of the long pintled hinges which permit the main sections, in the arrangement previously described, to be slid bodily longitudinally of 40 the car. The end sections are entirely eliminated and, in the space between the doorways, is placed a short auxiliary floor section, 25, which may be disposed of in any suitable way when not in use as, for example, 45 just beneath the ceiling in the center of the car as in my aforesaid application. Between the doors and each end of the car I then place a plurality of sections divided at the longitudinal center line of the car in the 50 same way as the section 6 in the arrangement previously described. In the arrangement shown, there are in addition to the section 25, four other sections, 26, each of these sections extending completely from the central 55 loose section 25 to one end of the car and from one side of the car to the longitudinal center line of the car. The sections 26 are connected to the side walls of the car in precisely the same way as are the end sections in 60 the other form of my invention. That is, the sections 26 are permitted to rotate through a quarter turn in order to bring them flat against the sides of the car, and then to travel upward by a sliding movement to 65 bring them into the upper regions of the

car; the guides 7, guiding members or heads 8 interlocked therewith, and connecting hinges between the members 8 and the auxiliary floor sections being the same as heretofore described. Suitable guides, 27, corresponding to the guides 13 and 14, in the other form, are adapted to engage the vertical edges of the several sections when the latter are slid upwardly. Suitable holding devices, such as the locks 15 heretofore described, are provided for holding the sections raised.

70 It will thus be seen that I have provided an extremely simple set of fixtures or attachments for connecting auxiliary floor sections to a car as permanently as has heretofore been the case where the floor sections have been simply hinged so as to fold up against the sides of the car and, in addition, I am enabled to keep the entire valuable 80 lower regions of the car entirely clear when the auxiliary flooring is not required; this being accomplished by fixtures and attachments including very little more than those that have been required for simple hinged 85 flooring.

90 While I have illustrated and described only a single preferred form of my invention, including a single modification, I do not desire to be limited to the exact structural details thus illustrated and described, but intend to cover all forms and arrangements which come within the terms employed in the definitions of my invention 95 constituting the appended claims.

100 I claim:

1. The combination with a car, of a loose auxiliary floor section and flexible connections between said section and the car permitting the same to rest on the floor of the 105 car and also to be swung up flat against a wall of the car and slid upwardly into the upper regions of the car.

2. The combination with a car, of a loose auxiliary floor section, flexible connections 110 between said section and the car permitting the same to rest on the floor of the car and also to be swung up flat against a wall of the car and slid upwardly into the upper regions of the car, and means for locking 115 said section against the side of the car when in its raised position.

3. The combination with a car, of a loose auxiliary floor section, flexible connections between said section and the car permitting 120 the same to rest on the floor of the car and also to be swung up flat against a wall of the car and slid upwardly into the upper regions of the car, and stationary guides for receiving the side edges of said section when 125 the latter is in its raised position.

4. The combination with a car, of a loose auxiliary floor section, flexible connections between said section and the car permitting 130 the same to rest on the floor of the car and

also to be swung up flat against a wall of the car and slid upwardly into the upper regions of the car, stationary guides for receiving the side edges of said section when the latter is raised and holding it against said wall, and movable supports for said section adapted to prevent it from dropping from its raised position.

5. The combination with a car, of a loose auxiliary floor section lying adjacent to a wall of the car, a member interlocked with said wall so as to be movable in the vertical direction from a position in the vicinity of the floor of the car and be held against movements in other directions, and a hinge connection between said member and the adjacent edge of the said floor section.

6. The combination with a car, of a loose auxiliary floor section lying adjacent to a wall of the car, a member interlocked with said wall so as to be movable in the vertical direction from a position in the vicinity of the floor of the car and be held against movements in other directions, a hinge connection between said member and the adjacent edge of the said floor section, and means for locking said section flat against said wall when said section is swung upwardly on its hinge against said wall and then moved upwardly parallel with said wall.

7. The combination with a car, of a loose auxiliary floor section lying adjacent to a wall of the car, a member interlocked with said wall so as to be movable in the vertical direction from a position in the vicinity of the floor of the car and be held against movements in other directions, a hinge connection between said member and the adjacent edge of the said floor section, stationary vertical guides constructed and arranged to interlock with the vertical edges of said floor section when the latter is swung upwardly about its hinge so as to lie flat against said wall and then moved upwardly along said wall.

8. The combination with a car, of a loose auxiliary floor section lying adjacent to a wall of the car, a member interlocked with said wall so as to be movable in the vertical direction from a position in the vicinity of the floor of the car and be held against movements in other directions, a hinge connection between said member and the adjacent edge of the said floor section, stationary vertical guides constructed and arranged to interlock with the vertical edges of said floor section when the latter is swung upwardly about its hinge so as to lie flat against said wall and then moved upwardly along said wall, and automatic locks arranged in position to engage with said floor section after the latter has been raised along said wall to a predetermined height and prevent the same from dropping down.

65 9. The combination with a car, of two

loose floor sections extending toward each other from opposite sides of the car and meeting at the longitudinal center line, and means for supporting each of said sections so as to permit it to be moved bodily in the vertical direction with one edge maintained in proximity to the corresponding side wall of the car and to swing angularly about that edge.

10. The combination with a car, of a loose auxiliary floor section, and flexible connections between the said section and an adjacent wall of the car for permanently securing said section to the car and permitting it to be swung upwardly through a quarter turn about its edge adjacent to the car and then to be slid upwardly along said wall.

11. The combination with a car, of a loose auxiliary floor comprising end sections in proximity to the end walls of the car and intermediate sections, flexible connections between the end sections and the end walls of the car permitting the sections to be swung from a position of rest on the floor of the car flat against the end walls and be slid upwardly along the end walls into the upper regions of the car, and flexible connections between the intermediate sections and the side walls of the car constructed and arranged to permit the intermediate sections to be shifted bodily in the longitudinal direction to clear the space between the doorways of the car and to be swung up flat against the sides of the car and slid upwardly into the upper regions of the car.

12. The combination with a car having a doorway in the side, a loose auxiliary floor section adapted to lie upon the floor of the car adjacent to said side and overlapping said doorway, and flexible connections between said sections and the car permanently connecting the two together and permitting said section to be moved longitudinally of the car far enough to clear said doorway and to be swung up against the side of the car and slid upwardly along said side into the upper regions of the car.

13. The combination with a car having a doorway in the side, a loose auxiliary floor section adapted to lie upon the floor of the car adjacent to said side and overlapping said doorway, and flexible connections between said section and the car permanently connecting the two together and permitting said section to be moved longitudinally of the car far enough to clear said doorway and to be swung up against the side of the car and slid upwardly along said side into the upper regions of the car, said connections being constructed and arranged to prevent the edge of the floor section next to said wall from moving away from said wall.

14. The combination with a car having a doorway in a wall thereof, of a loose auxiliary floor section adapted to rest on the main

car floor adjacent to said wall and overlapping said doorway, a vertical guide secured to said wall above said auxiliary floor section, a guiding head interlocked with 5 said guide and movable up and down the same, and a hinge connection between said guiding head and said floor section constructed and arranged to permit said floor section to be shifted bodily in the direction 10 of the length of the car a sufficient distance to bring it clear of the doorway and to be turned upwardly against the side of the car.

15. The combination with a car, of an auxiliary floor section adapted to rest on the floor of the car adjacent to a wall thereof, and a hinge one-half of which is permanently connected to said wall so as to be capable of sliding up and down while interlocked with the wall against movements 20 in other directions, the other half of the

hinge being secured to said section so as to hold it at all times with one edge near said wall and at the same time permit it to be swung upwardly against said wall and be moved bodily up and down with the hinge. 25

16. The combination with a car, of a loose sectional auxiliary floor adapted to rest on the main floor of the car, vertical guides or ways on the walls of the car in position to receive and interlock with the edges of said sections when the latter are laid flat against the lower portions of the car walls and are then slid upwardly along the same and hold the sections against the car walls, and means for holding the sections up after they are 30 35 raised.

In testimony whereof, I sign this specification.

WILLIAM T. VAN DORN.
